UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 13,950, dated May 29, 1883.

Application filed April 23, 1883. Term of patent 14 years.

To all whom it may concern:

Be it known that I, HERMAN IHLENBURG,
(assignor to MACKELLAR, SMITHS & JORDAN,) 5
of the city and county of Philadelphia, Pennsylvania,
have invented and produced a new and original Design for a Font of Printing-Type, of which the following is a specification.

The nature of my design is clearly shown in 10
the accompanying typographic impression, to which reference is made; and it consists of an unshaded letter composed of the heavy up and down portions having the scroll terminations, as shown, lighter than the letters which they 15
ornament.

The J, P, Q, R, S, V, W, X, Y, and Z are 20
extended below the line. The M and U do not have the scroll terminations. The right- 25

hand portion of the W is shorter than the left-hand portion. 20

The character of the design is preserved in the lower-case, the scroll termination being found in the d, g, j, k, p, v, x, and y, and the d, f, h, j, m, n, p, q, s, x, and y being extended below the line. The character of the design 25 is also preserved in the numerals.

Having now set forth my invention, I claim as new—

The design for a font of printing-type, as shown and described.

HERMAN IHLENBURG.

In presence of—
C. H. HUCH,
HERMAN METIUS.
